UNITED STATES PATENT OFFICE

RODGER EADES, OF WINCHESTER, KENTUCKY, ASSIGNOR OF ONE-FOURTH TO J. SMITH HAYS, OF WINCHESTER, KENTUCKY, AND ONE-FOURTH TO FLOYD H. McCLUNG, OF ASHLAND, KENTUCKY, AND HERBERT H. MOORE, OF WINCHESTER, KENTUCKY.

AUTOMATIC ELECTRIC SAFETY-GATE.

1,241,358.

Specification of Letters Patent. Patented Sept. 25, 1917.

Application filed November 15, 1916. Serial No. 131,492.

To all whom it may concern:

Be it known that I, RODGER EADES, a citizen of the United States, residing at Winchester, in the county of Clark and State of Kentucky, have invented new and useful Improvements in Automatic Electric Safety-Gates, of which the following is a specification.

This invention relates to crossing gates for railroads and of that type which are automatically operated through electric means to close the gates during the passing of a train in either direction, and to raise the gates after the train has passed. The primary object of the present improvements in automatically operating electrically controlled gates is to simplify the construction and arrangement of the parts of said gates and render them positive and reliable in their operation and also to provide means whereby the electric circuit which is closed to effect a lowering operation of the gates may be broken when a train is switching and during the time that the train is cut through at some point to open a crossing and whereby the gates are permitted to be raised automatically until the cut train is again connected for movement. The improved crossing gate also includes an arm that is put in operation to extend across a sidewalk simultaneously with the movement of the main street crossing or roadway guarding arm.

The invention consists in the construction and arrangement of the several parts which will be more fully hereinafter described and claimed.

In the drawings:

Figure 1 is a side elevation, partially broken away and in section, of a railroad or crossing gate embodying the features of the invention and showing the arms and the operating mechanism in normal position.

Fig. 2 is a horizontal section through the casing inclosing the gate operating mechanism and showing the arms in lowered position and also illustrating the operating devices in the positions they will occupy when a train comes into the electric block including the gate operating mechanism.

Fig. 3 is a detail view in longitudinal vertical section showing the gate operating mechanism.

Fig. 4 is a horizontal section illustrating

a part of the gate operating mechanism and embodying a slight modification in structure.

Fig. 5 is a section through the gate shaft gear and spring clutch co-operating therewith together with a part of the shaft.

Fig. 6 is an end elevation of the gate shaft gear particularly showing the shape of the spring clutch.

The numeral 5 designates a gate box or casing of suitable dimensions and disposed adjacent to a crossing. The gate box or casing 5 is divided into upper and lower compartments 6 and 7 by a horizontal partition 8, as clearly shown by Fig. 1, the upper compartment 6 containing the gate operating mechanism and the lower compartment 7 a part of the electric appliances. Within the compartment 6 an electric motor 9 is mounted and has an extended armature shaft 10 running to and engaging the upper extremity of a suitable bearing upright 11. On the shaft 10 a governor is mounted and comprises a slide 12 to which angular governor arms 13 are pivoted, the said arms being provided with the usual weights 14. The arms 13 extend through a slotted disk 16 secured on the shaft 10 to rotate with the latter. The arms 13 terminate in push head 16^a which engage a shifting disk 17 slidably mounted on the shaft 10 and also rotatable with the shaft, the said disk 17 having a hollow spindle 18 projecting therefrom and extending to and connecting with a friction gear disk 19. The disk 17, spindle 18 and friction gear disk 19 are of spool-like structure, and the said spindle is longitudinally slotted, as at 20, to permit a key pin 21 secured to the shaft 10 to project therethrough, a spring 22 surrounding the spindle between the pin 21 and the disk 17 and operating, when the disk 17 is relieved of pressure, to force the spindle 18 and the two disks 17 and 19 toward the motor 9 or to return these parts to normal position when permitted to do so.

Extending transversely of the gate box or casing 5 and mounted in suitable bearing devices is a gate operating shaft 23 having a suitable friction disk 24 of fiber or other material loosely mounted thereon and in position to be peripherally engaged by the friction gear disk 19, as shown by Fig. 2.

The one end of the shaft 23 projects outwardly beyond one side of the gate box or casing 5, and thereon a toothed segment 25 is secured and has an extension or attaching plate 26 continuing therefrom, said plate 26 being bolted or otherwise secured to a main gate arm 27 at a point distant from the inner end of the said arm so as to allow said arm to balance, a weight 28 being secured on the said adjacent end of this arm as in the usual type of gate arms employed at railroad and other crossings. On the same side of the gate box or casing 5 from which the shaft 23 projects, another segment 29 similar to the segment 25 is mounted on a stub shaft 30 and has an extension or attaching plate 31 bolted or secured to a sidewalk arm 32 which is of materially less dimensions than the arm 27, but of a length sufficient to extend across and guard a sidewalk, the two arms 27 and 32 moving in opposite directions owing to the intermeshing segments 25 and 29. The end of the shaft 23 within the gate box is a spring clutch or bowed plate spring 23^a having members 23^b bearing against the disk 24. This spring clutch 23^a is held in connection with the shaft 23 and adjustable through the medium of a screw 23^c engaging the inner end of the said shaft and provided with a set nut 23^d, which prevents the screw from working loose by binding against the end of the shaft, as clearly shown by Fig. 5. The disk 24 is adapted to bear against a collar 24^a fixed to the shaft 23, the said disk being pressed by the spring clutch 23^a against the collar 24^a to cause said gate shaft 23 to rotate to lower the gates, but when the gates are lowered and the motor continues to operate, the disk 24 will slip around on the shaft 23 and prevent breakage of the gates and driving mechanism.

Instead of using the friction gear disk 17 a bevel pinion 33 is connected to the tubular spindle 18 and the friction disk 24 on the shaft 23 is replaced with a bevel gear 34, as shown by Fig. 4, the pinion 33 being moved with the spindle 18 to mesh with the bevel gear 34. The remaining structural features shown by Fig. 4 are the same as those heretofore described and similar reference characters are applied thereto.

On one end of the gate box or casing 5 a signal bell 35 and a signal light 36 are mounted, the former being electrically connected to battery 37 by a wire 37^a and to the rail 40 by a wire 40^a; the light 36 being connected by wires 36^a and 36^b to the motor 9. The wire 36^a is intersected by an exteriorly operative switch 42. The switch 39 is electrically connected to the track rails at one side, for instance the rails 40, and to the motor by wires 39^a and 39^b. The battery 38 is connected by wires 38^a and 38^b to the rails 41 and motor 9. The electrical connections

relatively to the rails 40 and 41 will be of the usual electric block type, with the circuit normally open in view of the connection of the wires to the track rails as just explained, the locomotive bridging the rails 70 closing the circuit when first reaching the block which includes the bell 35 and the said bell in the daytime or the signal light 36 at night and the motor 9 are instantly operated and the gate arms 27 and 32 are lowered, 75 the circuit being broken through the switch 39 when the components of a train are required to be switched and at which time the train will be cut so as to give a passage-way therebetween in line with the roadway crossing the track rails. When the components of the train are again connected for progressive movement the switch 39 is closed and the gate arms which have been temporarily elevated will be again lowered and 80 remain in lowered position until the train passes out of the block. The signal light 36 will be used at night, and during daylight the switch 42 will be open, or the light circuit broken. It will be seen that the batteries 37 and 38 are both connected to the rail 41, the battery 37 by wire 37^b and the battery 38 by wire 38^b, and hence the electrical circuit will be closed and the motor and signal devices actuated by the movement of 95 cars over the rails 40 and 41 within the electrical block provided.

What is claimed is:

1. In a railroad crossing gate of the class specified, the combination of an electric motor having an extended armature shaft, a governor mounted on the shaft and having expanding arms with free ends, gear shifting means slidably mounted on said shaft and rotatable therewith, the gear shifting means being provided with a gear device and a part thereof having the free ends of the expanding governor arms in loose contact therewith to push the gear shifting means, a gate operating shaft carrying a gate arm and having a gear which is engaged by the gear device of the gear shifting means, and electrical block connections and a source of electrical generation for actuating the motor and gate arm. 110

2. In a railroad crossing gate of the class specified, the combination of a motor having an extended armature shaft with a governor slidably mounted thereon and provided with arms having free ends, a spring-actuated gear shifting means also mounted on the said shaft and having a disk at one end in engagement with the free ends of the governor arms and the opposite end provided with a gear device, a gate arm operating shaft having gate arms thereon and also provided with a gear with which the said gear device has engagement at intervals, a source of electrical generation, and electrical block connections for a rail- 130

road track and providing circuits in which the motor and source of electrical generation are included.

3. In a railroad crossing gate of the class specified, the combination of a motor having an extended armature shaft, a governor mounted on the motor and having expanding arms with free ends, a gear shifting member slidably mounted on said shaft and 10 rotatable therewith and having a disk at one end loosely engaged by the free ends of the governor arms, the gear shifting member having a gear device, a gate operating shaft carrying a gate arm and having 15 a gear loosely mounted thereon with which said gear device is thrown into operative engagement, a spring clutch means engaging one face of the said loosely mounted gear for holding the said gear on the gate 20 arm shaft in sufficiently tight engagement with the latter shaft to effect a lowering of the arm but permitting the said gear to run free when the arm is fully lowered or raised, and electrical block connections and 25 a source of electrical generation for actuating the motor and gate arm.

4. In a railroad crossing gate of the class specified, the combination of a gate arm having a shaft with a gear loosely mounted thereon and provided with a recess in one 30 face, the shaft at one end being continued as a screw terminal, a fixed collar on the shaft engaging the recess in one face of the gear, a spring clutch plate fitted over the screw terminal and having arms 35 engaging the adjacent face of the gear, clamping and set devices engaging the screw terminal to hold the spring clutch in position, an electric motor having shifting means including a gear device to engage the 40 loosely mounted gear on the gate arm shaft, and electrical connections for the motor for automatically operating the latter and the gate arm.

In testimony whereof I have hereunto set 45 my hand in presence of two subscribing witnesses.

RODGER EADES.
